ABSTRACT

A ski brake for slowing down and stopping the movement of a ski on a slope when the ski boot slips out of the ski binding. The ski brake preferably comprises a U-shaped member having a transverse portion located, during use of the ski, between the top face of the ski and the front end of the sole of the ski boot and a pair of legs extending closely adjacent to opposite side faces of the ski forwardly of the transverse portion, and a leaf spring attached at opposite ends to the transverse portion and the top face of the ski and biased to tilt the U-shaped member, when the boot slips out of the ski binding, to a position in which the U-shaped member includes an angle with said top face and the legs will dig into the snow beneath the bottom face of the ski.

FIG. 1

FIG. 2

FIG. 3

SKI BRAKE

BACKGROUND OF THE INVENTION

The present invention relates to a ski brake for slowing down and stopping the movement of a ski on a slope when the ski boot slips out of the ski binding.

The sport of skiing has increased considerably in the last few years, and so have the accidents occurring during skiing. One of the reasons for such accidents are "runaway" skis which become disengaged from the skier when one or both of the boots of the skier slip out from the respective ski binding and the ski or skis continue their fast path down the slope so that the runaway ski may strike another skier or a person standing on the ski slope and causes injury to such persons. To recapture such runaway skis is also difficult and sometimes impossible so that the user may be left stranded on a mountain from which the descent without skis may be difficult and dangerous.

Attempts have already been made to correct such situations by binding the skis to the skier by means of straps, for example attached to the ankles of the skier. In this way, the skis cannot run away from the skier during a fall of the latter and the skier can then easily reattach the skis to the ski-boots. One disadvantage of fastening the skis in the aforementioned manner to the ankles of a skier is that, especially during a fall of the skier, the skis will be held closely adjacent to the body of the falling skier which may cause injury to the user.

SUMMARY OF THE INVENTION

It is an object of the present invention to overcome the above-mentioned disadvantages and to provide a ski brake for slowing down and stopping movement of a ski on a slope when the ski boot of the skier slips out of the ski binding.

It is a further object of the present invention to provide a ski brake which can be easily mounted in a convenient manner on any type of ski.

It is an additional object of the present invention to provide a ski brake which consists of few and simple parts so that the ski brake may be manufactured at reasonable cost and will stand up properly under extended use.

With these and others objects in view, which will become apparent as the description proceeds, the ski brake according to the present invention for slowing down and stopping the movement of a ski on a slope when, during skiing, the boot of the skier slips out of the ski binding, mainly comprising a mobile member having a portion extending transverse to the top face of the ski and at least one elongated prong integral at one end with said transverse portion and located laterally of a side face of the ski, in which the mobile member is located, when the boot of the skier is held by the ski binding against the top face of the ski, in an inactive position in which the transverse portion is held between the sole of the ski boot and the top face of the ski while the elongated prong extends substantially parallel to a side face and adjacent to the top face of the ski, and in which biasing means connected to the ski and the mobile member bias the latter from the inactive to an active position assumed by the mobile member under the influence of the biasing means when the boot slips out of the binding and in which the transverse member and the prong is tilted with respect to the top face of the ski

so that the free end of the prong will extend beneath the bottom face of the ski to dig into the snow thereunder.

Preferably, the ski brake includes two prongs which project forwardly from the transverse portion of the mobile member and which are located closely adjacent and parallel to the side faces of the ski.

With such a ski brake attached to the ski, the biasing means which are held in substantially flat tensioned condition by the ski boot, when the latter abuts against the transverse portion of the mobile member, will assume a curved substantially untensioned rest position, when the ski boot slips out of the ski binding and releases the transverse portion of the mobile member, to thereby tilt the mobile member with respect to the top face of the ski so that the free ends of the prongs will dig into the snow beneath the bottom face of the ski which will rapidly brake and finally stop further movement of the ski to which the brake is connected. The danger that the loose ski will cause injury to the user or to other persons on the ski slope which may be struck by the runaway ski is thus avoided.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a perspective view of a ski brake according to the present invention before attaching the same to a ski;

FIG. 2 is a partial longitudinal cross section through a ski with the ski brake shown in FIG. 1 attached thereto and showing the brake in an inactive position in which it is held by the front end of a ski boot when the latter is connected to the ski by the ski binding; and

FIG. 3 is a partial cross section similar to FIG. 2, but showing the ski brake in an active position it will assume when the ski boot has slipped out of the ski binding.

DESCRIPTION OF THE PREFERRED EMBODIMENT

FIG. 1 illustrates a ski brake according to the present invention before it is attached to a ski. The ski brake preferably comprises a substantially U-shaped member having a transverse portion 3 and a pair of prongs or legs 4 projecting forwardly from the transverse portion. The brake includes further biasing means, which are preferably in form of a leaf spring 1 formed from spring steel which is located with a major portion thereof between the legs 4 of the U-shaped member and which is attached at one end by rivets 2 or the like to the transverse portion 3 of the U-shaped member, whereas the leaf spring 1 is provided in the region of its opposite end with a pair of elongated slots 6 extending transverse to the elongation of the leaf spring for fastening the latter by means of screws or the like to the top face of a ski. In the unstressed position shown in FIG. 1 the leaf spring 1 is curved along part of a cylindrical surface. The U-shaped member is preferably formed from plastic material, such as polycarbonate or polyamide, which has at low temperatures a high resistance against

bending. The legs or prongs 4 have preferably substantially triangular cross section profiled at the outer faces thereof by longitudinally extending grooves 5 formed in the outer faces of the prongs.

The transverse portion 3 of the U-shaped member is preferably covered on its upper surface thereof by a thin plate 7 formed from a material having a low coefficient of friction, for instance polytetrafluoroethylene, available on the market under the tradename of Teflon.

As shown in FIG. 2, the ski brake is attached to the ski 8, shown in part in cross section, by means of screws 13 extending through the slots 6 in such a manner that the vertical plane of symmetry of the brake corresponds to that of the ski. The ski brake is attached to the upper surface of the ski in such a position so that during normal use of the ski the transverse portion 3 of the brake is located between a front portion of the sole of a ski boot 9 and the upper surface of the ski, which will tension the leaf spring 1 by flattening the same until it assumes a planar position parallel to and abutting against the top face of the ski.

The ski boot 9 is during use fixedly held between the front unit 10 and the rear unit 11 of a safety ski binding known in the art and not forming part of the present invention which is constructed to release, during a fall of the skier, the ski boot from the ski. In the position of the ski boot 9 as shown in FIG. 1, the front portion of the sole of the ski will rest on the thin plate 7, whereas the legs 4 will be positioned laterally and closely adjacent and substantially parallel to opposite side face of the ski and substantially at the level of the top face of the ski.

In this inactive position the ski brake will not hinder in any way the movement of the skis on the snow 12 even if the skis assume, when the skier makes a sharp turn, a position transversely inclined to the surface of the snow since in this position the grooves 5 formed at the outer faces of the prongs 4 will prevent any braking contact of these prongs with the snow.

If, for some reason whatsoever, the ski boot 9 slips out of the ski binding, the elastic biasing means 1 will curve upwardly at the rear end thereof which is attached to the transverse portion 3, the moment the tension applied thereto by the sole of the ski boot is released, which will result in tilting of the U-shaped member to the position shown in FIG. 3 so that the prongs 4 will project downwardly and forwardly relative to the bottom face of the ski 8. In this position, the prongs will dig into the snow 12 and the movement of the ski in the direction of the arrow f is instantaneously braked and finally stopped due to the reaction imparted by the prongs in the direction indicated by the arrow f' onto the snow. The displacement of the ski boot 9 relative to the ski is not at all hampered by the ski brake since the portion of the boot sole engaging the transverse portion of the U-shaped member can easily slide laterally thereon due to the plate 7 mounted on the transverse member and having a low coefficient of friction.

The ski brake according to the present invention will assure that the ski at such occasion in which the ski boot slips out of the ski binding will not run away on a slope and can be easily recovered, while accidents which could be produced by a runaway ski are positively avoided.

It will be understood that each of the elements described above, or two or more together, may also find

a useful application in other types of ski brakes differing from the types described above.

While the invention has been illustrated and described as embodied in a ski brake for slowing down and stopping movement of a ski when during skiing the boot of the skier slips out of the ski binding, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

1. In combination with a ski having a top face, a bottom face and a pair of longitudinal side faces, and a ski binding having a front and a rear unit for releasably holding a ski boot on the top face of a ski, a ski brake for slowing down and stopping the movement of the ski when, during skiing, the boot slips out of the ski binding, said ski brake comprising a mobile member of plastic material having at low temperatures a high resistance against bending, said member being substantially U-shaped and having a portion extending transverse to the longitudinal direction of the ski and two elongated prongs each integral at one end with and projecting from said transverse portion towards the front end of the ski and located laterally and closely adjacent to the respective side face of the ski, said mobile member being, when the boot of the skier is held by the ski binding against the top face of the ski, in an inactive position in which said transverse portion is located between a front portion of the sole of the ski boot and the top face of the ski while said elongated prongs extend substantially parallel to and adjacent to the respective side faces of the ski in the region of the top face of the latter, said mobile member being movable, when the boot slips out of the binding, from said inactive to an active position in which said transverse member and said prongs are tilted with respect to said top face so that the free end portions of said prongs will project beneath the bottom face of the ski to dig into the snow beneath the latter; and biasing means for biasing said mobile member from said inactive to said active position and comprising a leaf spring fixedly attached at one end to said transverse portion and at the other end to the top face of the ski in the region of the front unit of the ski binding.

2. A ski brake as defined in claim 1, wherein said plastic material is taken from the group consisting of polyamides and polycarbonates.

3. A ski brake as defined in claim 1, and including a thin plate of a material having a low coefficient of friction connected to the upper surface of said transverse portion.

4. A ski brake as defined in claim 3, wherein said plate is formed from polytetrafluoroethylene.

5. A ski brake as defined in claim 1, wherein said prongs have a substantially triangular cross section.

6. A ski brake as defined in claim 5, wherein each of said prongs has a inner face adjacent and substantially parallel to the corresponding side face of the ski and an outer face including an acute angle with said inner face and being provided at this outer face with a longitudinally extending groove.

7. A ski brake as defined in claim 1, wherein said leaf spring in unstressed condition is curved along part of a

cylindrical surface.

8. A ski brake as defined in claim 7, wherein said leaf spring is fixedly attached at one end to said transverse portion of said mobile member and provided in the region of its other end with elongated slots extending transverse to the elongation of the ski for attaching the leaf spring to the top face of the ski by means of screws.
